UNITED STATES PATENT OFFICE.

WILLIAM ISLER, OF CANTON, OHIO, ASSIGNOR TO THE BERGER MANUFACTURING COMPANY, A CORPORATION OF OHIO.

LOCKER DOOR.

Application filed May 3, 1928. Serial No. 274,942.

This invention has for its object the provision of a door for a locker or other enclosure, the various parts of which may be quickly and readily formed and assembled, 5 which will be extremely rigid and sturdy in construction, and which will present with a neat and attractive appearance.

Another object of the invention is to provide a hollow metal door for a locker or 10 other enclosure, so that a latching bar may be advantageously inserted in the edge portion of the door and hidden from view at all times. By thus concealing the latching bar from view, the temptation to tamper 15 with it is more or less completely obviated.

Another and more specific object of the invention is to provide a locker door having an especially designed arrangement of louvers adapted to provide ample ventilation for the interior of the locker, as well 20 as to prevent the entry of small objects into the hollow door and liquids into the interior of the locker.

These and other objects of the invention 25 will become more readily apparent in the course of the following description of the invention, taken in connection with the accompanying drawings, wherein—

Fig. 1 is a front elevation of a locker in 30 which is embodied the novel features of the present invention;

Fig. 2 is a rear elevation of the locker door;

Fig. 3 is a cross-section through the door 35 and adjacent portions of the locker, taken on the line 3—3 of Fig. 1;

Fig. 4 is a cross-section through a portion of the door and latching bar, taken on the line 4—4 of Fig. 3, and

Fig. 5 is a cross-section through the locker door, taken on the line 5—5 of Fig. 2.

Referring more particularly to the drawings, the locker includes a sheet metal frame 1, and a door 2 hinged thereon, as by means 45 of hinges 3.

The door 2 consists of a front panel 4 and a rear panel 5. The front panel 4 is provided at the top and bottom edges with flanges 6 and 7, respectively, and at the sides 50 with an L-flange 8 and a flange 9, a portion of the latter being offset by means of a shoulder 10. The front panel is further provided near the top and bottom with outwardly pressed and downwardly extending 55 ventilating louvers 11, and is also provided

at the opposite side edges with spaced slots 12 and 13, the slots 12 serving to receive the leaves of hinges 3, and the slots 13 adapted to receive tenons 14 of a handle 15.

The rear panel 5 of the door is provided at 60 the top and bottom edges with flanges 16 and 17, respectively, and at the sides with flanges 18 and 19. The rear panel is further provided near the top and bottom with inwardly pressed and upwardly extending vent 65 tilating louvers 20, and extending between the upper and lower groups of louvers is a channel reinforcing bar 21, the legs 22 of which are secured to the inner face of the panel, as by spot welding. This channel 70 also serves to space the front and rear panels from each other, and prevents inward buckling of the rear panel, which is usually made of lighter gauge sheet metal than the front panel. Holes 23 spaced to correspond with 75 the slots 12 in the front panel are provided at one edge of the rear panel to facilitate connection of the hinges 3 to the front panel, and also to facilitate spot welding of flanges 9 and 19 to each other at these points when 80 the door is assembled. Spaced slots 24 are provided near the other edge of the rear panel, these slots being adapted to receive the hook-like portions 25 of keepers 26 secured to the frame 1 of the locker. 85

The front and rear panels are assembled as shown in Figs. 3 and 5, and are welded to each other in any desired manner.

A channel latching bar 27 having slotted latching clips 28 secured to the web thereof 90 at spaced intervals, is then inserted in the edge portion of the door through a suitable opening 29 left in the flanges 7 and 17 of the front and rear panels. The bar is then pushed up into the door to a position where 95 the web of the bar may be engaged by tenons 14 of the handle 15.

Inwardly pressed lugs 30 are provided on the rear panel, and these serve to confine the latching bar in the edge portion of the 100 door.

When the door is closed, the hook-like portions 25 of the keepers 26 enter the slots in the latching clips 28 to effect positive latching of the door. The operation of the keepers in effecting such positive latching is clearly described in copending application of Joseph Sturm and William L. Caldwell, Serial No. 115,538. 105

As clearly shown in Fig. 5, louvers 11 in the 110

front panel are pressed outwardly and extend downwardly, and are directly opposite louvers 20 in the rear panel, which are pressed inwardly and extend upwardly. 5 This arrangement of the louvers provides ample ventilation for the locker, and at the same time, the outer face of the rear panel is left without any undesirable projections which would reduce the available interior 10 locker space. Moreover, as lockers are used to a considerable extent by children, who would be normally inclined to drop small objects into the hollow door if the louvers 20 were pressed inwardly and extended downwardly, such occurrences are obviated to a considerable extent by providing the rear panel with upwardly extending louvers. 15 The aforesaid arrangement of the louvers also prevents entry of water into the in-

terior of the locker, when, as often happens, 20 the locker is drenched with water during a fire.

Claims:

1. The combination of spaced front and rear metal panels forming a hollow door, a 25 latching bar enclosed in the edge portion of said door, and lugs pressed inwardly from the metal of said rear panel and confining the latching bar to the edge portion of the door.

2. The combination of spaced metal panels forming a hollow door, a latching bar enclosed in the edge portion of said door, and lugs pressed inwardly from the metal of one of said panels and confining the latching bar to the edge portion of the door. 35

In testimony whereof I affix my signature.
WILLIAM ISLER.
